Primary Examiner—Robin V. Webster*(74) Attorney, Agent, or Firm*—McCarter & English, LLP(57) **CLAIM**

We claim, the ornamental design for a dispenser nozzle, as shown and described.

DESCRIPTION

FIG. 1 is a side perspective view of a dispenser showing our new design.

FIG. 2 is a top plan view of the dispenser of FIG. 1.

FIG. 3 is a right side view of the dispenser of FIG. 1.

FIG. 4 is a side view of the dispenser if FIG. 1; and,

FIG. 5 is a bottom plan view of the dispenser of FIG. 1. The broken line showing is for illustrative purposes only and forms no part of the claimed design.
